UNITED STATES PATENT OFFICE.

HARRY J. STEINBERGER, OF SKIATOOK, OKLAHOMA.

WORKING VALVE FOR OIL WELLS.

Application filed March 18, 1922. Serial No. 544,702.

To all whom it may concern:

Be it known that I, HARRY J. STEINBERGER, a citizen of the United States, residing at Skiatook, in the county of Tulsa and State 5 of Oklahoma, have invented new and useful Improvements in Working Valves for Oil Wells, of which the following is a specification.

In the drilling of oil wells at the present 10 time the outer wall of the chamber of the working valve is equipped with a series of packing elements that surround the chamber concentrically thereof in juxtaposition one to the other. These packing elements engage the inner wall of the working valve 15 and are used to form a fluid tight joint between the valve and barrel, so that in the operation of the valve the oil will be forced through the valve to the surface. Owing 20 to the sandy condition of the soil from which the oil is obtained the oil carries a certain amount of the sand with it, and this floating sand works in between the valve and the barrel, thereby coating the packing elements 25 and rendering them leaky, thus destroying the value of the packing and reducing the efficiency of the working valve.

My invention is designed to overcome this 30 objectionable feature heretofore present in the operation of the working valve and is designed to prevent or minimize the passage of the sand into the space between the working valve and the barrel, thereby prolonging the life of the packing and enabling 35 the working valve to operate efficiently and effectively in the operation of the well.

Another purpose of my invention is the 40 provision of auxiliary packing means for the working valve which cooperates with the usual packing elements to form a fluid tight joint between the valve and the barrel, and wherein my improved packing means may be readily removed and replaced whenever necessary.

45 It is also my purpose to provide an improved packing means for the working valve which will embrace the desired features of simplicity, efficiency and durability and which will act at all times to form an effective fluid tight joint between the valve and the barrel, thereby enabling the working valve to operate at its highest efficiency in the operation of the well.

With the above recited objects in view, 55 and others of a like nature, my invention

resides in the construction, combination and arrangement of parts set forth in and falling within the scope of the appended claim.

In the accompanying drawings:

Figure 1 is a side elevation of the working valve constructed in accordance with my invention.

Figure 2 is an enlarged fragmentary vertical sectional view through the upper end of the working valve.

Figure 3 is a similar view through the central portion of the working valve.

Figure 4 is a like view through the lower end of the working valve.

Figure 5 is an enlarged vertical sectional view through the working barrel, showing the portion of the working valve therein equipped with my invention.

Referring now to the drawings in detail, and particularly to Figure 5, A designates 75 a portion of the working barrel, the upper end of which is connected with the lower end of the well casing (not shown) and the bottom end of which is equipped with the usual standing valve (not shown), as is well 80 known.

Working within the barrel A is my improved working valve shown as an entirety in Figure 1 of the drawings. In accordance with my invention this valve is composed 85 of a main or central tubular section 1 and top and bottom end sections 2 and 3 respectively. Adjacent to its upper end the main or central section 1 is circumferentially reduced as at 4 and is formed with an exteriorly threaded nipple 5 contiguous to the reduced portion 4. This nipple 5 is threaded into an enlarged bore 6 formed in the lower end of the top section 2 contiguous to the bore of such section. At its lower end the main or central section 1 is exteriorly threaded to engage in a relatively large bore 7 formed in the upper end of the bottom section 3. These sections 1, 2 and 3 when connected together as shown in Figure 1 of 100 the drawings, form the working valve casting and the bores thereof are in axial alignment so as to provide a continuous unbroken passage for the oil in the operation of the working valve.

As a point between the threaded lower end and the upper portion of the central section 1, the latter is of reduced external diameter and surrounding this portion of the section 1 are packing elements. In the pres- 110

ent instance these packing elements are in the form of metal and leather rings 8 and 9 respectively. The metal rings 8 are tapered downwardly and the leather rings 9 are cup shaped and have their walls surrounding the tapered portions of the adjacent metal washers as clearly illustrated in Figure 3 of the drawings. The leather rings alternate with the metal rings and are designed to engage the inner wall of the working barrel in the operation of the working valve, so as to form a fluid tight joint between the barrel and the valve, the leather packing ring having a tendency to expand against the inner wall of the barrel in the operation of the valve.

These metal and leather washers alternating one with the other are used at the present time around the working valve, but in the operation of the valve the floating sand in the oil works up into contact with these packing elements, and as a consequence the leather washers are cut up and their utility destroyed, thus destroying the fluid tight joint between the valve and the barrel and permitting the oil to leak by the valve. As a consequence the efficiency of the working valve is materially lessened.

The bottom section 3 of my improved working valve is formed of two parts 10 and 11, as clearly shown in Figure 4 of the drawings. The upper part 10 has its upper end connected with the lower end of the main or central section 1, as in Figure 3, while the lower end of such part 10 is formed interiorly with an enlarged bore 12, and threaded into this bore 12 is a nipple 13 formed on the upper end of the bottom part 11. Contiguous to the nipple 13 the outer surface of the upper portion of the part 11 is circumferentially reduced as at 14.

In accordance with my invention the lower end of the top section 2 contiguous to the circumferential reduced portion 4 cooperates with such reduced portion to form a groove, while the lower end of the part 10 of the lower section cooperates with the circumferential reduced portion 14 on the lower part 11 to constitute a packing ring groove, as clearly illustrated in Figures 2 and 4 of the drawings. In each of these grooves I fit an expandible metal packing ring 15. In the present instance each ring 15 is of the split type and the ends thereof at the split portion are cut out laterally and overlap each other, so as to prevent leakage through the ring.

In the present instance the upper end of the top section 2 is formed to provide a valve seat, and engaging this seat is a ball check 16, while surrounding the ball check and threaded onto the upper end of the section 2 is a valve cage 17 housing the check 16. The upper end of the cage 17 is threaded to receive the tubular valve rod that is

designed to communicate with the working valve in the operation of the latter to convey the oil to the surface.

In accordance with my invention the parts of the section 3 are knurled as at 18—18 respectively, while the main section 1 adjacent to its upper end is knurled as at 19, and the top section 2 knurled as at 20. These knurled portions are circumferentially reduced and provide grips to receive wrenches or similar tools in order to facilitate the taking down of the sections of the working valve when it is necessary to renew the rings 15.

In practice, the working valve fits within the working barrel, as illustrated in Figure 5, and the rings 15 arranged above and below the packing elements 8 and 9 engage the inner surface of the working barrel. These rings being metal and expansible tightly engage the barrel so that in the operation of the working valve sand and other foreign substances are prevented from passing the rings, and thereby contacting with the leather packing rings 9. Thus the life of the packing rings is prolonged and the efficiency of the working valve enhanced so that in the continued operation of the working valve the latter may function to its full capacity and with a minimum of wear on the parts.

From the foregoing description, taken in connection with the accompanying drawings, it will be seen that I have provided a working valve and packing arrangement therefor which may be easily and quickly taken down when it is necessary to renew the rings 15 and the rings 8 and 9, and wherein the parts are so arranged and correlated as to reduce the possibility of derangement to a minimum.

While I have herein shown and described one preferred form of my invention by way of illustration, I wish it to be understood that I do not limit or confine myself to the precise details of construction herein shown and described, as modifications and variations may be made within the scope of the claim and without departing from the spirit of my invention.

I claim:

In a working valve for oil wells, the combination with the working barrel, of a working valve comprising a central section engageable with the adjacent wall of the barrel, packing elements surrounding said central section and engageable with the adjacent wall of the barrel to form a fluid tight joint, top and bottom end sections connected to said central section, the lower end section being formed of two parts detachably connected together, one of said parts being circumferentially reduced at its juncture with the other part to provide an annular groove, a metal packing ring within said groove and covering the meeting ends of the sections,

said central section at its upper end being circumferentially reduced and formed with a threaded extension of less diameter than the circumferentially reduced portion, the 5 top end section being threaded onto said extension and being of greater diameter than the circumferentially reduced portion of

said central section and cooperating with said circumferentially reduced portion to form a groove and an expansible metal packing ring carried in said last named groove. 10

In testimony whereof I affix my signature.

HARRY J. STEINBERGER.
